DESIGN FOR A LAPEL PIN

Frederick J. Pearsall, Clayville, R. I., assignor to Imperial Pearl Co., Inc., Providence, R. I., a corporation of Rhode Island

Application August 3, 1946, Serial No. 132,258

Term of patent 3½ years

(Cl. D45—19)

To all whom it may concern:

Be it known that I, Frederick J. Pearsall, a citizen of the United States, residing at Clayville, in the county of Providence and State of Rhode Island, have invented a new, original, and ornamental Design for a Lapel Pin, of which the following is a specification, reference being had to the accompanying drawing, forming part thereof.

Fig. 1 is a plan view of a lapel pin, showing my new design; and

Fig. 2 is a side view of the same.

I claim:

The ornamental design for a lapel pin, as shown.

FREDERICK J. PEARSALL.
